UNITED STATES PATENT OFFICE.

HILMA S. SWANSON, OF KANSAS CITY, MISSOURI.

DESIGN FOR A TOASTER.

SPECIFICATION forming part of Design No. 35,144, dated October 1, 1901.

Application filed August 19, 1901. Serial No. 72,608. Term of patent 14 years.

To all whom it may concern:

Be it known that I, HILMA S. SWANSON, a citizen of the United States, residing at Kansas City, in the county of Jackson and State 5 of Missouri, have invented and produced a new and original Design for Toasters, of which the following is a specification.

My invention relates to a design for toasters; and my object is to produce a new and 10 original design for the same which is both ornamental and useful.

In the accompanying drawings, which illustrate the design, Figure 1 represents a plan view of a toaster embodying my new design. 15 Fig. 2 is a vertical longitudinal sectional view of the same, taken on line II II of Fig. 1.

As shown in the drawings, the leading or material feature of my design consists of a circular pan 1, having a peripheral annular 20 groove 2, terminating in a flange 3 at its

outer side and a horizontal plane 4 at its inner side.

5 designates a slotted handle which extends from one side of the pan.

6 designates a wire mat which rests upon 25 the convex side of the annular groove, and 7 designates the prongs extending from the rim of the mat down through perforations 8 in the pan.

Having thus described my invention, what 30 I claim, and desire to secure by Letters Patent, is—

The design for a toaster, substantially as herein shown and described.

In testimony whereof I affix my signature 35 in the presence of two witnesses.

HILMA S. SWANSON.
